(57) **CLAIM**

We claim the ornamental design for an electrical connector, as shown and described.

DESCRIPTION

FIG. 1 is a front elevation view of an electrical connector showing our new design;

FIG. 2 is a rear elevation view of the electrical connector;

FIG. 3 is a top plan view of the electrical connector;

FIG. 4 is a bottom plan view of the electrical connector;

FIG. 5 is a left side elevation view of the electrical connector;

FIG. 6 is a right side elevation view of the electrical connector;

FIG. 7 is a perspective view of the front and left side of the electrical connector; and,

FIG. 8 is a reduced top plan view of the electrical connector in a connecting condition. The printed circuit board and the counterpart electrical connector are drawn in broken lines for illustrative purposes only and form no part of the claimed design.
